UNITED STATES PATENT OFFICE.

CHARLES HOLDRIDGE SMITH, OF COUNCIL BLUFFS, IOWA, ASSIGNOR OF
ONE-THIRD TO HARRY L. SMITH, OF SAME PLACE.

SYSTEM OF RETAINING HEAT AND OF VENTILATION.

SPECIFICATION forming part of Letters Patent No. 665,351, dated January 1, 1901.

Application filed March 5, 1897. Serial No. 626,158. (No model.)

To all whom it may concern:

Be it known that I, CHARLES HOLDRIDGE SMITH, of Council Bluffs, Pottawattamie county, State of Iowa, have invented a certain new and Improved System of Retaining Heat and of Ventilation, of which the following is a specification.

This invention relates to heating apparatus, and an embodiment thereof will be hereinafter described and the invention definitely pointed out in the claims.

At the present time and under the present known systems of heating it is a well-known and recognized fact that a very large portion of the heat is carried off and escapes through the chimney or flue. My invention is designed to overcome this objection, and I have discovered that this large per cent. of heat can be controlled, so as to prevent its escape, and utilized, and, further, by the application of the invention it has been found by actual and numerous tests and uses that not only will the invention or discovery prevent the escape of heat or heated gases to a great degree, but will also largely prevent unnecessary and useless consumption of fuel. I have also discovered in connection with my invention that the carbonaceous products, usually in the form of smoke, cinders, and soot, which heretofore have been carried off and wasted are by my apparatus wholly or substantially wholly consumed and as such are utilized as fuel for the production of additional heat.

My invention and discovery is, as far as I know, a radical departure from any system, method, and means heretofore suggested, and while I have shown an embodiment of the same in the accompanying drawings I desire it understood that the invention is in no sense limited to the construction shown.

I have discovered that by employing an auxiliary flue of a capacity substantially that of the chimney or main flue and that by so positioning and arranging a portion of the auxiliary flue that either a horizontal current, or a current not directed upward, of air will pass through the flue and be deflected into the chimney and by conducting the products of combustion from the heat-generator and into the auxiliary flue at or near the horizontal portion in a manner hereinafter described and

permitting at the same time a free passage of air through the auxiliary flue the above-mentioned desirable results are attained.

In the drawings, Figure 1 is a perspective view of an apparatus embodying my invention. Fig. 2 is a perspective of a slightly-modified construction.

Referring to the drawings, and particularly to Fig. 1, 1 indicates a heat-generator in the form of an ordinary or any preferred form of stove. 2 indicates a chimney or main flue, which may be of the usual or any approved construction and size and, as shown, is built in the wall of the apartment or building in which the stove is located, though this is not essential, and the flue may be in the form of an exposed pipe. Leading to the chimney or main flue 2 is an auxiliary cold-air flue 3, which to produce best results is of the same or substantially the same capacity as the chimney or flue 2. The cold-air flue is provided with a substantially horizontal portion or course (indicated at 7) and with a substantially horizontal additional course or bend 8, connecting the portion 7 directly with the main flue or chimney 2. The flue 3 has an open intake end located at any point where a supply of cold or cool air is obtainable and, as shown, is located near the floor 4 of the apartment or building in which the generator is located. 12 is a damper for closing the intake of the flue 3 when the fire is to be started in the generator. From the generator or heater leads a pipe or flue 6, which, as shown, connects with the portion or course 7 of the flue 3 opposite the course or bend 8, the pipe 6 serving as the conductor for the heated products or products of combustion from the generator to the flue portion 7. 5 indicates an extension of the flue 3 for the purpose of obtaining the cold-air supply from another point.

In Fig. 2 substantially the same relative arrangement of the chimney, cold-air flue, and heated-products flue is shown; but in this construction the generator is shown in the form of a furnace and the air-flue is represented as provided with a plurality of intake branches, (indicated at 3^a), the aggregate capacity of which branches is substantially equal to that of the cold-air flue, which

latter, like the corresponding flue in Fig. 1, is substantially of the same capacity as the chimney or main flue.

From the above-described construction and arrangement I have found by large numbers of actual demonstrations where the apparatus has been in practical use for a considerable period of time, covering in many instances an entire year, that the above-mentioned saving of fuel and heat is accomplished.

The apparatus and invention, as will be readily understood, is in no sense that of the ordinary damper or check-draft which is now widely known and used, and I have found that the best results are obtained when that portion of the air-flue into which the smoke-flue discharges is arranged in either a substantially horizontal position or a position not extending upward toward the exit, and my experience has shown that a flue extending upward with a single bend into the chimney and into which the smoke-flue enters will not accomplish the same results, although I do not wish to be understood as limiting my invention to the particular construction of the elbow portion.

Having thus described my invention, what I claim as new, and desire to secure by Letters Patent, is—

30 1. In a heating apparatus, the combination with a primary or main flue, of a heater having a smoke-flue, and means for supplying air to the main flue across the exit of the smoke-flue in a substantially horizontal direction and into the main flue in line with the smoke-flue, substantially as described.

2. In a heating apparatus, the combination with a main flue of a heater having a smoke-flue and means for conducting a volume of 40 air across the mouth of the smoke-flue in substantially a horizontal direction and deflecting the air at an angle into the main flue, substantially as described.

3. In a heating apparatus, the combination 45 with a main flue, of a heater, an air-flue having a substantially horizontal portion the end of which horizontal portion extends at an angle to the main part thereof and enters the main flue, and a smoke-flue leading from the heater into the horizontal portion of the air-flue intermediate its ends, substantially as described.

4. In a heating apparatus, the combination

with a main flue, of a heater, an air-flue having a substantially horizontal portion one 55 part of which extends at an angle to the main part and enters the main flue, and a smoke-flue leading from the heater into the main part of said horizontal portion of the air-flue opposite the angular part, substantially as 60 described.

5. In a heating apparatus, the combination with a heater, of a main flue, an auxiliary flue having a capacity substantially that of the main flue, and having a portion extending transverse to and at an angle into the main flue and a smoke-flue entering the transverse portion of the auxiliary flue, substantially as described.

6. In a heating apparatus, the combination 70 with a main flue, of a heat-generator, an auxiliary cold-air flue leading from a point at or near the floor, having a portion arranged substantially horizontal and its end leading at an angle into the main flue and a smoke-flue leading from the heater into the horizontal portion of the auxiliary flue opposite the inlet to the main flue, substantially as described.

7. In a heating apparatus, the combination 80 with a main flue and a heater, of an auxiliary flue having a capacity substantially that of the main flue terminating at its intake end at or near the floor, and having a transverse portion and an angle portion, and a smoke-flue leading from the heater into the transverse portion of the auxiliary flue, substantially as described.

8. In a heating apparatus, the combination 90 with a substantially vertical main flue or chimney, of a supplemental air-flue of a capacity substantially that of the main flue or chimney, and having a horizontal portion 7 and a portion 8 at an angle to the portion 7 and entering the main flue or chimney, a generator, a pipe 6 leading from the generator, and entering the portion 7 of the supplemental air-flue opposite and in line with the portion 8 of the supplemental air-flue, substantially as described.

In testimony whereof I have hereunto set my hand this 25th day of February, A. D. 1897.

CHARLES HOLDRIDGE SMITH.

In presence of—

C. E. HAWLEY,
M. E. GOOLEY.
